UNITED STATES PATENT OFFICE.

PHILIP H. VOIGT AND OSCAR C. KUEHNE, OF HOUSTON, TEXAS.

WINDING-DRUM.

1,111,333.

Specification of Letters Patent. Patented Sept. 22, 1914.

Application filed September 3, 1913. Serial No. 788,030.

To all whom it may concern:

Be it known that we, PHILIP H. VOIGT and OSCAR C. KUEHNE, citizens of the United States, residing at Houston, in the county of Harris, State of Texas, have invented a new and useful Winding-Drum, of which the following is a specification.

The present invention relates to improvements in winding drums, one object of the invention being the provision of a drum structure in which the rope engaging portion is composed of a plurality of longitudinally slidable members, each one of which is provided with a portion of a rope guiding and engaging flange, whereby the primary coil placed thereupon will be guided out of the way of the next succeeding coil during the winding operation, thus preventing the overlapping of the coils during the winding operation and thus also preventing any undue strain being thrown upon the cable.

A further object of the present invention is a winding drum of this character, in which means is provided for longitudinally sliding the various sections of the drum during the rotary action of the drum.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a longitudinal sectional view through a complete drum embodying the present invention. Fig. 2 is a section taken on the line 2—2 of Fig. 1. Fig. 3 is a perspective view of one of the section actuating cams of the drum as shown in Fig. 1. Fig. 4 is a perspective view of one of the sections of the drum removed, the same being broken away to show the cross sectional structure thereof. Fig. 5 is a cross section through one of the sections. Fig. 6 is a view similar to Fig. 1 of a modified form of winding drum. Fig. 7 is a perspective view of one of the sections thereof. Referring to the drawings, and more par-

ticularly to Fig. 1 through 5, two supporting heads 1 and 2 are provided, there being journaled therein the operating shaft 3, 55 which has keyed thereon, the spool 4 by means of the key 5. This spool 4 is provided with the disk heads 6, which as clearly shown in Fig. 2 are provided with a plurality of peripheral slots 7 for the reception 60 of the ribs 8 carried by the respective sections or staves 9 which constitute the rope receiving or winding drum of the present invention. These sections, as clearly shown in Figs. 1 and 4, are provided with slots 65 10—10' respectively in the ends thereof and in each slotted portion is journaled its respective roller 11—11'.

Secured fixedly to the inner face of each of the respective heads 1 and 2, is a disk 70 12—12', each one of which carries its respective cam rim 13 provided with the lowered or depressed portion 14. Disposed between the cam rims 13, as clearly shown in Fig. 1, and adapted to engage the same, are 75 the rollers 11—11', which as the shaft 3 is rotated and the spool 4 is consequently rotated also imparts longitudinal movement to the respective staves or sections 9 and thus moves the lugs or bosses 15, one to each of 80 the sections 9 and which constitute the rope guiding flange, so that the first coil of the rope wound thereon will be abutted by one of the moving lugs 15, or as clearly shown in the lower portion of Fig. 1, so that the uppermost lug will be separated from the rope and in a position to permit the next coil to rest upon the drum. By this means, 85 the overlapping of the coils is prevented and the coils as they are fed upon the drum are 90 moved toward the right, as shown in Fig. 1, and consequently when led off in the opposite direction after three or four coils have 95 been placed thereon, do not tend to produce undue friction due to the shortening of the cable as is the case when the coils overlap. It will thus be seen, that the various lugs or bosses 15 constitute a rope receiving flange upon the sectional drum and that by the action imparted to the respective sections due 100 to the cams 13 and the abutting ends of the sections, the relative positions of the bosses or lugs 15 are changed particularly at the desired point to cause the proper positioning

or feeding of the coils longitudinally of the drum.

In order to provide a means whereby one of the heads as head 2, may be dispensed with, a structure as shown in Fig. 6 is provided. In this structure, the supporting member 17 is provided with a receptacle portion and has secured therein, the disk 18, the same being held in place by means of the screws or bolts 19. The member 17 is provided with the cam rim 20 which is in alinement with the cam rim 21 of the member 18, the same being in spaced relation for the purpose as will presently appear. A cam shaft 22 is journaled in the member 17 and carries the spool 23 having the rims 24 and 25. A head 26 is connected by bolts 28 to the annular rim 29 of the spool 23 so as to rotate therewith. The sections or staves 30, are each provided with the flange forming boss or lug 31, and with a rib 32 which corresponds to the rib 8 of the stave 9, said rib being disposed for longitudinal movement in the recessed peripheries of the disks 24 and 25, the inner end of said sections being disposed within the member 17. Connected to each of the ends of the sections 30 within the member 17 by means of a pin 33 is an anti-frictional roller 34, said roller being disposed to abut the respective cam rims 20 and 21 and thus as the drum 33 is rotated, cooperates with these cams to impart the desired longitudinal sliding movement to the respective staves or sections 30. By this means it will be seen, that the operation of means for controlling the sections is at one end only and not at two ends as shown in Fig. 1. This form of drum is particularly employed when it is desired to slip the rope off and on the drum, the head 26 in this case permitting this action, and the member 17 being lagged or otherwise secured fixedly in place.

What is claimed is:

1. A device of this character, including a support having two heads; a drum rotatably mounted between the heads and composed of a plurality of longitudinally slideable cable receiving sections, each one of which is provided with a section of a cable guiding flange; and coöperative means carried by each head and in the ends of the sections for imparting successive sliding movement to the sections as the drum is revolved.

2. A device of this character, including a support having two heads; a drum rotatably mounted between the heads and composed of a plurality of longitudinally slideable cable receiving sections, each one of which is provided with a section of a cable guiding flange, and coöperative means carried by each head and the sections for imparting successive sliding movement to the

sections as the drum is revolved; said co-operative means including a cam carried by each head of the support and a cam engaging means carried in the end of each section.

3. A device of this character, including a support having two heads, a spool mounted therebetween for rotation, a plurality of staves slidably connected to the periphery of the spool and constituting the cable receiving surface, means carried by each section and constituting a portion of the cable and guiding flange of the drum, and coöperating means carried by the ends of each stave and the heads of the support for imparting successive longitudinal sliding movement to the staves as the spool is rotated.

4. A device of this character, including a support having two heads, a spool mounted therebetween for rotation, a plurality of staves slidably connected to the periphery of the spool and constituting the cable receiving surface, means carried by each section and constituting a portion of the cable and guiding flange of the drum, and coöperating means carried by the end of each stave and the heads of the support for imparting successive longitudinal sliding movement to the staves as the spool is rotated, said coöperating means including a cam mounted in each head of the support, and cam engaging means carried in each end of the staves.

5. In a device of this character, a support, a shaft journaled therein, a sleeve having two disks one at each end thereof constituting the spool of a drum, a plurality of sections, coöperating means carried by the sections and the disks for holding the sections against circumferential movement but permitting longitudinal reciprocatory movement thereof, said sections constituting the cable receiving portion and with the spool constituting a drum, means carried by each stave and coöperating with the same means of the other staves to form a cable guiding means, and coöperating means carried by the staves and the support for imparting successive longitudinal reciprocatory movements to the staves as the drum is revolved.

6. In a device of this character, a support, a shaft journaled therein, a sleeve having two disks one at each end thereof constituting the spool of a drum, a plurality of sections, coöperating means carried by the sections and the disks for holding the sections against circumferential movement but permitting longitudinal reciprocatory movement thereof, said sections constituting the cable receiving portion and with the spool constituting a drum, means carried by each stave and coöperating with the same means of the other staves to form a cable

guiding means, coöperating means carried by the staves and the support for imparting successive longitudinal reciprocatory movements to the staves as the drum is involved, said coöperating means including a cam, and cam engaging means carried by the stave end for engaging the cam.

In testimony that we claim the foregoing

as our own, we have hereto affixed our signatures in the presence of two witnesses. 10
